UNITED STATES PATENT OFFICE.

CHARLES W. WYMAN, OF CLAREMONT, NEW HAMPSHIRE, ASSIGNOR TO SULLIVAN MACHINERY COMPANY, A CORPORATION OF MASSACHUSETTS.

CONNECTER.

Application filed December 27, 1920. Serial No. 433,410.

My invention relates to connectors or contact making devices, and more particularly to devices for use in coal mining for the purpose of making running and fixed contact with the trolley wires employed in the entries of such mines.

An object of my invention is to provide an improved device of the type mentioned. A further object of my invention is to provide an improved contact making device provided with improved means for maintaining the same connected to a trolley wire and for preventing its accidental detachment therefrom. A further object of my invention is to provide an improved trolley clip having an enclosed removable fuse provided with an improved mounting whereby the fuse may be readily removed or changed as desired. Other objects of my invention will appear in the course of the appended specification and claims.

In the accompanying drawings, I have shown for purposes of illustration, one form which my invention may assume in practice.

In these drawings,—

Fig. 1 is a view in elevation, with parts broken away to show details of the internal construction, of the illustrative form of my improved contact device.

Fig. 2 is a central longitudinal section on line 2—2 of Fig. 1.

Figs. 3 and 4 are transverse sections on lines 3—3 and 4—4, respectively, of Fig. 2.

In coal mining, mining machines having electric driving motors are much used and these motors receive their current from trolley wires strung around the various entries of the mine. The mining machine is generally arranged in such a manner upon its truck that the motor of the mining machine likewise is operable to drive the truck. As it is desirable to make the operation of the machine as simple as possible and to maintain the head room required as low as possible, fixed trolley poles are not generally used but instead a manually grasped contact device provided with a heavy wire to contact with the trolley wire is generally used. This is arranged at the free end of the wire wound upon the reel carried by the machine or its truck and is held in contact with the trolley wire by the miner as the machine proceeds from place to place.

When the machine reaches a point where it

is desired to make a cut, this manual trolley is secured in some convenient manner to the wire and the machine runs in to the cutting face unreeling the wire from its reel as it moves.

In the illustrative embodiment, I have shown my invention removably attached to a wire 1 which may be connected, for example, to the motor (not shown) of a mining machine. The device comprises generally a grasping portion 2 comprising a tube 3 of insulating material, and a contact element generally indicated by 4 provided with an automatic clamp 5 adapted to be removably attached to a trolley or feeder wire, the element 4 herein also having a socket 6 in which a trolley clip or piece of heavy wire may be inserted to make detachable contact with the trolley wire during running of the machine from place to place. The automatic clamp 5 comprises fixed and movable jaws 7 and 8 and means for normally maintaining them in contact enclosed in a housing 9. The insulating shell 3 of the grasping portion 2 is of hollow construction as indicated at 10 and within the same is arranged a fuse bearing block generally indicated by 11. This comprises front and back head members 12 and 13, each of brass or other suitable metal and an intermediate fuse carrying member 14. The latter is composed of two members, that designated 15 being of fiber and adapted to provide the necessary strength, while that designated 16 is of asbestos or a similar preparation and adapted to resist the arc formed upon the blowing of the fuse as later described. The members 15 and 16 are secured together by suitable rivets 17 and an air space 18, to protect the member 15 from the heat generated by the passage of the current through the fuse or by the blowing of the latter, is arranged between the two in the center, this being done because the member 15 being in some cases of fibrous material, might be burned by the heat generated at the fuse. The member 15 at its rear end is secured by a plurality of rivets 19 to the metallic end member 13 and at its forward end is secured to the second metallic contact member 12 by a plurality of rivets 20. The contact member 12 is provided with a conical nose 21 for the purpose of insuring a good and ample contact area with the member 4. The contact member 4 is of reduced diameter at its rear portion, here designated 110

4', in order to fit the front end of the tube 3 and is provided with a conical socket 22 to cooperate with the member 21 and is likewise provided with automatically operable means to clamp itself, the fuse block, and other elements later to be described within the member 3. This mechanism comprises a pair of telescopically arranged members 23 and 24 each projecting radially from opposite sides of the member 4 and adapted respectively to enter openings 25 and 26 formed in the shell member 3 and in a lining sleeve 27 in the front end thereof. A spring 28 imparts to the members 23 and 24 a normal tendency to separate and a stop pin 29 prevents their separation to a too great extent. Obviously when the members 23 and 24 are in a position to project through the openings 25 and 26, pressure applied to their opposite ends by the thumb and forefinger will compress or telescope these members in such a manner as to permit their passing through the sleeve member 27 and thereby permit withdrawal of member 4 as a whole.

23 The members 12 and 13 are provided with undercut slots 31 and 30 respectively to receive the opposite ends of a removable fuse link 32 and this fuse is adapted to be held in place by suitable screws 33 and 34. For 30 the purpose of preventing the insertion of a fuse of a greater capacity than that desired, a non-adjustable steel limit screw 35, having its top surface flush with the top of the member 12, is arranged rearward of the screw 34 35 and set so as to prevent insertion of a fuse or fuses of an excessive total capacity. The removal fuse links 32 are provided with projecting portions 36 adapted to raise the portion 37 of reduced area, in which it is desired that the fusing shall take place, out of contact with the member 16 in such manner as to protect that member to the maximum degree.

45 For the purpose of rendering the fuse readily replaceable, it has been arranged, as already described, so that the fuse carrier may be readily withdrawn through the forward end of the member 3. I, preferably, arrange a spring 38 between the member 13 50 and a member 39 which is secured to the cable member 1, and connect the members 13 and 39 by means of a flexible conductor 40 so that the spring 38, which is prevented 55 from carrying current by means of annular insulating sleeves 41, arranged on adjacent ends of members 13 and 39, may have its function limited solely to an elastic pressure means. It will be noted that the cable 1 is of a less size than an opening 42 through which 60 it enters the rear end of the handle 3 and accordingly the entire apparatus contained in the interior of the member 3 can be caused to move out through the front end thereof. Attention is also directed to the fact that 65 the conductor or wire 1 which may be the

trailing cable of a mining machine, is removably connected to the member 39 as by a plurality of screws 43, in such a manner as to enable the device to be connected or disconnected from that conductor when desired. 70

From the foregoing description, the mode of operation of this device will be readily apparent. When a fuse has blown, the members 23 and 24 are released from their engagement with the openings 25 and 26 and the front member 4 is removed. The fuse carrier 11 and the member 39 are then readily likewise passed toward and through the forward end of the member 3 for a sufficient distance to permit the replacing of the fuse, the use of a fuse of too heavy capacity being prevented by the stop screw 35. When the fuse has been replaced, the members 39, 14, and 4 are forced back into the member 3 and held in position by means of the members 23 and 24. The spring 38 insures a good contact between the conical nose 21 on the member 12 and socket 22 on the member 4. 80

85 While I have in this application specifically described one form which my invention may assume in practice, it will be understood that this form of the same is shown for purposes of illustration and that the invention may be modified and embodied in other forms without departing from its spirit or the scope of the appended claims.

What I claim as new and desire to secure by Letters Patent is:—

1. In an electric connector, a pair of spatially separated contact devices provided with laterally opening sockets for the reception of a fuse, a renewable fuse arranged in said sockets and connecting said contact devices, and means adjacent the mouth of one of said sockets to limit the size of fuse insertable therein. 100

2. In an electric connector, a pair of spatially separated contact devices provided with sockets for the reception of a fuse, a removable fuse arranged in said sockets and connecting said contact devices, and means comprising a non-adjustable stop member projecting partially into one of said sockets to limit the size of fuse insertable therein, 110 said stop member at its outer end being flush with the outer surface of the contact device on which it is located. 115

3. In an electric connector, a fuse carrying member comprising contact devices at each end thereof and intermediate insulating means comprising a spacing member, a non-inflammable protective plate therefor, and means forming an air space intermediate a portion of said protective plate and said spacing member. 120

4. In an electric connector, a fuse carrying member comprising contact devices at each end thereof and intermediate insulating means comprising a spacing member, a non- 130

inflammable protective plate therefor spaced for a portion of its length from said spacing member whereby a protective air space is provided, and a fuse connecting said contact devices and overlying said protective plate and having its portion of maximum resistance disposed adjacent said air space.

5. In an electric connector, a fuse carrying member comprising contact devices at each end thereof and intermediate insulating means comprising a spacing member, a non-inflammable protective plate therefor spaced for a portion of its length from said spacing member whereby a protective air space is provided, and a fuse connecting said contact devices and overlying said protective plate and having its portion of maximum resistance disposed adjacent said air space, and provided with means to maintain said portion out of contact with said protective plate.

6. In an electric connector, a pair of spacially separated contact devices, a fuse connecting the same, an insulating member enclosing said fuse, and means for maintaining said fuse and said contacts within said insulating member comprising a conducting member having a pair of manually compressible locking elements engaging said insulating member.

7. In an electric connector, a pair of spacially separated contact devices, a fuse connecting the same, an insulating member enclosing said fuse, and means for maintaining said fuse and said contacts within said insulating member comprising a conducting member having a pair of manually compressible telescopic locking elements engaging said insulating member.

8. In an electric connector, a pair of spacially separated contact devices, a fuse connecting the same, an insulating member enclosing said fuse, means for maintaining said fuse and said contacts within said insulating member, comprising a conducting member closing one end of said insulating member and a trailing wire extending into the other end thereof, and means for elastically pressing one of said contact devices into contact with said conducting member.

9. In an electric connector, a pair of spacially separated contact devices, a fuse connecting the same, an insulating member enclosing said fuse, means for maintaining said fuse and said contacts within said insulating member, comprising a conducting member closing one end of said insulating member and a trailing wire having electrical connection with said fuse, said connection being enclosed by said insulating member, and elastic means cooperating with one of said contact devices to press the other thereof into contact with said conducting means.

10. In an electric connector, a pair of spacially separated contact devices, a fuse connecting the same, an insulating member en-

closing said fuse, means for maintaining said fuse and said contacts within said insulating member, comprising a conducting member closing one end of said insulating member, and elastic means cooperating with one of said contact devices, but insulated therefrom, to press the other thereof into contact with said conducting means.

11. In an electric connector, an insulating manual grasping member, a contact member arranged at one end thereof and adapted for connection to one wire of a circuit, a flexible connection at the other end thereof to the other wire of the circuit, a replaceable fuse inside said grasping member, and means for preventing the substitution of a fuse of excessive capacity.

12. In an electric connector, an insulating manual hollow grasping member, a contact member releasably secured to one end thereof, a member arranged adjacent the other end thereof and flexibly connected to one wire of a circuit, a fuse carrying member arranged between said contact member and said third mentioned member, a flexible connection between said fuse carrying member and said third mentioned member, and a surface connection between said fuse carrying member and said second mentioned member.

13. In an electric connector, an insulating manual grasping member provided with a bore, a contact member adapted for connection to one wire of a circuit attached to one end thereof, a member at an opposite end thereof connected to the other wire of said circuit, and a fuse carrying member arranged within said grasping member and elastically pressed into contact with one of said other members.

14. In an electric connector, an insulating member, a contact member arranged at one end thereof and locked therein, and having a conical seat formed therein, a member in the opposite end of said insulating member connected to one wire of a circuit, a fuse carrying member within said insulating member and connected to said last mentioned member, and a spring between said fuse carrying member and said last mentioned member, said fuse carrying member being provided with a conical plug adjacent one end thereof cooperating with the conical seat in said contact member.

15. In an electric connector, an insulating manual grasping member, a contact member arranged at one end thereof and releasably locked therein, a member in the opposite end of said grasping member connected to one wire of a circuit, a fuse carrying member within said grasping member and flexibly connected to said last mentioned member, a spring between said fuse carrying member and said last mentioned member, said fuse carrying member being provided with a conical plug adjacent one end thereof coop-

erating with a conical seat in said releasable contact member, said fuse carrying member comprising a pair of metallic end members, an intermediate insulated spacing member, 5 and a non-combustible protecting plate adjacent which a fuse is secured.

16. In an electric connector, an insulating manual grasping member, a contact member arranged at one end thereof and releasably 10 locked therein, a member in the opposite end of said grasping member connected to one wire of a circuit, a fuse carrying member within said grasping member and flexibly connected to said last mentioned member, a 15 spring between said fuse carrying member and said last mentioned member, said fuse carrying member being provided with a conical plug adjacent one end thereof cooperating with a conical seat in said releasable 20 contact member, said fuse carrying member comprising a pair of metallic end members, an intermediate insulated spacing member,

and a non-combustible protecting plate adjacent which a fuse is secured, said fuse having a point of maximum resistance, and said non-combustible member and said spacing member being separated by an air space at a point adjacent the point of maximum resistance in said fuse member. 25

17. In an electrical connector, an insulated manual grasping member provided with a bore, a contact member adapted for connection within said member and adjacent said grasping portion to one wire of a circuit attached to one end thereof, a member at the 30 opposite end thereof connected to the other wire of said circuit, a fuse, and a fuse carrying member supporting said fuse at both ends and arranged within said grasping member and pressed into contact with one of 35 said first mentioned members.

In testimony whereof I affix my signature.

CHARLES W. WYMAN.
